CLAIM

The ornamental design for a boat windshield, as shown and described.

DESCRIPTION

FIG. 1 is a front perspective view showing the exterior of a boat windshield;

FIG. 2 is a rear perspective view showing the interior of the boat windshield of FIG. 1;

FIG. 3 is a front view of the boat windshield of FIG. 1;

FIG. 4 is a rear view of the boat windshield of FIG. 1;

FIG. 5 is a top view of the boat windshield of FIG. 1;

FIG. 6 is a side view of the boat windshield of FIG. 1 (the other side view being a mirror image thereof); and,

FIG. 7 is a bottom view of the boat windshield of FIG. 1.

The broken lines are for the purpose of illustrating portions of the article that form no part of the claimed design.
